[57] CLAIM

The ornamental design for a healing cap for a dental implant, as shown and described.

DESCRIPTION

FIG. 1 is a bottom perspective view of a healing cap for a dental implant showing our new design;

FIG. 2 is a perspective view taken from above the healing cap shown in FIG. 1;

FIG. 3 is a bottom view of FIG. 1;

FIG. 4 is a left side view of FIG. 1;

FIG. 5 is a top view of FIG. 1;

FIG. 6 is a right side view of FIG. 1;

FIG. 7 is a bottom perspective view of a second embodiment of the healing cap for a dental implant;

FIG. 8 is a perspective view taken from above the healing cap shown in FIG. 7;

FIG. 9 is a bottom view of FIG. 7;

FIG. 10 is a left side view of FIG. 7;

FIG. 11 is a top view of FIG. 7; and,

FIG. 12 is a right side view of FIG. 7.
